UNITED STATES PATENT OFFICE

2,641,855

DREDGE BUCKET CONSTRUCTION

Thomas C. Whisler, Alameda, Calif., assignor to
American Brake Shoe Company, New York,
N. Y., a corporation of Delaware

Original application October 16, 1947, Serial No.
780,232. Divided and this application June
30, 1949, Serial No. 102,385

4 Claims. (Cl. 37—191)

1

The invention relates to chain dredge buckets and has reference more particularly to an improved dredge bucket comprising separable parts and including a hood portion provided with a depending annulus and a base portion having an opening for receiving the annulus.

In the manufacture of chain dredge buckets it has been the practice to cast the buckets in the form of solid or integral castings of manganese steel. In the casting of large structures radical changes exist in the metal sections from top to base so that foundry difficulties are often encountered. For eliminating such difficulties in the casting of large bucket structures the invention contemplates making the hood portion of the bucket separate from the base member and in providing special features in the design of the parts whereby they can be conveniently fitted together. More particularly, as contemplated by the invention, the base member will be provided with a circular opening for receiving a depending annulus formed on and integral with the hood portion and which is adapted to fit in the base opening for releasably securing the parts in assembled relation.

Accordingly, an object of the invention is to provide an excavating bucket of separable construction which will comprise a plurality of parts in order to avoid foundry difficulties in the casting of the parts and wherein the same are so designed as to have interfitting relation for joining the parts to comprise an assembled unit.

Another object of the invention is to provide a separable chain bucket construction with the hood and base portions being interchangeable to facilitate assembling in the field or replacement of the parts.

With these and various other objects in view, the invention may consist of certain novel features of construction and operation, as will be more fully described and particularly pointed out in the specification, drawings and claims appended hereto.

In the drawings which illustrate an embodiment of the device and wherein like reference characters are used to designate like parts—

Figure 1 is a side elevational view illustrating a separable two-part dredge bucket constructed in accordance with the invention, certain portions being shown in section to clearly illustrate structural details;

Figure 2 is a side elevational view of the hood portion of the bucket; and

Figure 3 is a top plan view illustrating structural features of the base portion.

2

Referring to the drawings, the chain dredge bucket selected for illustrating the invention essentially consists of a hood portion 10 comprising the excavator body of the bucket and a base portion 12 to which the hood is releasably secured. The hood comprises a cup-like structure having a substantially continuous bounding wall generally designated 13, a front portion 14 and a rear portion 15. In cross section on a transverse approximately horizontal plane the inside contour of the hood is substantially elliptical, the inside wall 16 forming the rear and the bottom of the bucket and merging with the side walls of the same which terminates at 13.

To cooperate with the hood 10 there is provided a removable member forming a separate lip 18. The lip is customarily cast in manganese steel as is also the base and hood portions, and the contour of the lip is such as to coincide with the marginal wall 13 of the hood. The lip is thus crescent-shaped in plan, being preferably fabricated in one piece and is provided with inside and outside flanges 20 and 21, respectively, for straddling the marginal wall of the hood portion. For a more particular description of the straddling flange structure for the lip 18 reference is made to my Patent No. 2,228,546 of January 14, 1941 entitled Excavator. Said lip in the vicinity of the rear portion thereof is provided with a plurality of apertured bosses 22 which cooperate with similar bosses 23 formed integral with the hood portion. Fastening bolts 24 extend through aligned apertures of the bosses respectively and function to securely fasten the lip to the hood portion with provision being made for conveniently releasing the lip for purposes of repair or replacement.

A circumferentially extending ledge or wall 25 is integral with the hood portion 10 having location adjacent the bottom of the hood portion. Said wall 25 on each side of the hood portion is provided with a plurality of slots 26 for receiving fastening bolts to be presently described in detail and this slotted section of wall 25 is reinforced by vertically extending ribs 27 having location on the exterior of the hood portion and which merge with the wall 16 thereof.

In accordance with the invention the hood and base portions of the bucket are separable, the hood portion having a depending annulus indicated by numeral 28, Figure 1, and which depends from the wall 25, being integral therewith and integral with the wall 16 of the hood as shown in Figure 1. The depending annulus 28 may be reinforced by ribs such as 30 having location within the open bottom of the same. It will

be observed that the bottom surface of wall 25 and the exterior surface of depending annulus 28 are both machined to provide smooth surfaces which are accordingly designed to have a close fit with cooperating surfaces provided by the base portion 12. Details of the base portion will now be described.

Since chain dredge buckets are adapted to have articulated relation with other buckets to form an endless conveyor the base portion 12 as shown in Figure 1 has cast integral therewith a rear boss 31 which is pierced at 32 for receiving the back eye bushing 33. The rear boss 31 is located centrally with respect to the longitudinal center line of base portion 12 and said boss is somewhat less in width than the overall width of the base. The front is accordingly provided with a pair of front bosses 34 which are pierced to provide front eyes 35 and which receive a pin for the purpose of articulately connecting adjacent buckets. It will be understood that the pin will extend through the front eyes 35 and through back eye bushing 33 of the adjacent bucket with the pin being journalled by said bushing which accordingly takes the wear during operation of the chain conveyor.

In addition to the rear and front bosses the base portion 12 includes a substantially horizontally disposed top wall 36 which is machined to provide a flat surface complementary to that provided by wall 25. Also wall 36 includes a depending wall 37 which is circular in extent to define an opening 39 of a size for receiving the depending annulus 28 whereby the hood portion is united with the base portion to form a unitary structure comprising a chain dredge bucket. As previously explained, wall 25 is formed with slots 26 for receiving fastening bolts 38 which pass through aligned openings in wall 36 of the base portion. Securing nuts 40 are provided for said fastening bolts which therefore serve to securely but releasably hold the hood portion in assembled relation with the base portion. As a result of the separable construction of the portions forming the present chain bucket it is possible to cast each portion without encountering foundry difficulties which would otherwise be the case if the hood and base portion were cast as one piece, particularly as regards large buckets. Foundry difficulties are eliminated since as regards each portion radical changes in metal sections have been eliminated. It is necessary, as is the case of fitting the lip to the hood portion, to have the hood and base casting interchangeable. With separable parts in accordance with the invention it is possible to bore the opening in the base portion to a plug gauge and to machine the depending annulus of the hood portion so as to fit a ring gauge and accordingly there will be no question about interchangeability in the field which also makes for convenience in the replacement of parts during use of the bucket.

The opening 39, as defined by the wall 37 of the base portion is such as to require reinforcing means for the base portion and accordingly the side wall members 41 and 42, Figure 3, are joined by a transverse rib 43 located below the opening and disposed substantially diametrically of the same. This rib ties together the wall members 41 and 42 at a point approximately centrally of their length and said rib is in turn connected to the rear boss 31 by the spaced parallel ribs 44 and 45. Vertical ribs 46 are located on the exterior surface of each side wall member

and said ribs extend from the top wall 36 to the bottom wall and merge with their respective side walls 47 or 48 which define the side limits of the base member. The construction is such as to form compartments on each side of the base member and in each compartment securing screws 49 are located having threaded relation with their respective bolts 38 which depend through openings 50 in the top wall 36 and by means of which the separable parts of the present bucket are secured in assembled relation.

This application is a division of my copending application Serial No. 780,232, filed October 16, 1947, and now abandoned, and entitled Dredge Bucket Construction.

The invention is not to be limited to or by details of construction of the particular embodiment thereof illustrated by the drawings as various forms of the device will of course be apparent to those skilled in the art without departing from the spirit of the invention or the scope of the claims.

What is claimed is:

1. An excavator bucket, in combination, a hood portion providing a dredge bucket and having a depending annulus, a base portion having an opening centrally thereof for receiving the depending annulus whereby the hood and base portions may be joined in assembled relation, securing means for releasably securing the said portions in assembled relation, and reinforcing means for the base portion including a rib integral with the base portion and extending substantially diametrically of the opening below the same.
2. An excavator bucket, in combination, a hood portion providing a dredge bucket and having an outwardly extending bottom wall, an annulus depending from said bottom wall centrally of the same, a base portion having a flat top wall and side walls, said top wall having a center opening for receiving the depending annulus and said bottom wall of the hood portion and the top wall of the base portion having coacting machined surfaces for a close fit when the portions are assembled, securing means for releasably securing the said portions in assembled relation, and reinforcing means for the base portion including a transverse rib joining the side walls and extending substantially diametrically of the opening below the same.
3. An excavator bucket, in combination, a hood portion providing the bucket proper and having an exterior of generally spherical shape, an annulus integral with the hood portion and depending from the bottom thereof, a circumferential wall extending laterally outwardly from the hood portion at the junction of the annulus therewith, vertically disposed ribs on the exterior of the hood portion for joining and reinforcing the circumferential wall with respect to the hood portion, a base portion having a flat top wall and side walls, said top wall having a center opening for receiving the depending annulus to unite the hood and base portions in assembled relation, said top wall and said circumferential wall having coacting machined surfaces for a close fit when the portions are assembled, securing means extending through aligned openings in said circumferential wall and top wall for releasably securing the portions in assembled relation, and reinforcing means for the base portion including a transverse rib joining the side walls and extending substantially diametrically of the opening.

4. An excavator bucket, in combination, a hood portion providing the bucket proper and having an exterior of generally spherical shape, an annulus integral with the hood portion and depending from the bottom thereof, a circumferential wall extending laterally outwardly from the hood portion at the junction of the annulus therewith, vertically disposed ribs on the exterior of the hood portion joining and reinforcing the circumferential wall with respect to the hood portion, a base portion having a flat top wall and having side walls so disposed that the top wall extends laterally beyond each side wall, said top wall having an opening located approximately centrally thereof between the side walls for receiving the depending annulus to unite the hood and base portions in assembled relation, said top wall and said circumferential wall having co-acting machined surfaces for a close fit when

5 the portions are assembled, and securing bolts extending through aligned openings in said circumferential wall and top wall for releasably securing the portions in assembled relation, the openings in the top wall for the securing bolts being located to the outside of the side walls respectively in the laterally extending sections of the top wall.
